APPARATUS FOR SPREADING SPLIT BARS
TO CIRCULAR FORMSThomas R. Landers, Holyoke, Mass., assignor to
Moore Drop Forging Company, Springfield,
Mass., a corporation of Massachusetts

Application March 14, 1951, Serial No. 215,574

1 Claim. (Cl. 153—48)

1

This invention relates to an improved method and apparatus for spreading steel bar stock or billets of steel into ring shape for drop forging work and has for its object to provide economy in the fabrication of rings of extremely hard and tough steel compositions.

Another object of the invention is to provide novel mechanism which will prevent wastage of expensive stock normally incident to the usual method employed in drop forging such rings.

Another object of the invention is to form rings for drop forging work of the type disclosed in appreciably less time than is employed under prior methods of operation.

A further object is to provide apparatus of a simplified type which will permit greater utilization of available drop hammer equipment in a drop forging shop.

These and other objects and advantages will be seen from the following disclosure of the invention in connection with the accompanying drawings.

In the drawings,

Fig. 1 is a top plan view of the apparatus in open position with a split billet shown disposed in position for the spreading operation;

Fig. 2 is a side view of the apparatus as shown by Fig. 1;

Fig. 3 is an end view on line 3—3 of Fig. 2;

Fig. 4 is a top plan showing the parts of the apparatus in closed position with the ring halves spread;

Fig. 5 is a side view of the parts as shown by Fig. 4 with the ring in section; and

Figs. 6 to 10 are views showing successive steps in the formation of a ring.

It has long been a general practice to forge steel rings by upsetting a billet or block of stock into ring shape by pounding the stock over a plug and thus spreading the steel gradually. The ring is then brought to shape for any fullering, trimming, and blocking die operations with a thinned down web in the center which must be cut or punched out for the ring to be forged in finish dies and subsequently brought to size.

In working steels of a hard and tough alloy composition this type of operation is excessively time consuming, wasteful of expensive material, and requires the use of several preliminary forging die blocks. Two or more drop hammers may

2

be necessary to progressively form a ring from the bar stock since the work piece must be alternately heated and pounded until the desired shape is achieved. It has also been found that in making rings of certain types of steel that formation of the ring in the drop hammer dies results in a high percentage of scrap in view of the inability of the material to withstand the action of rapid hammer blows.

10 It will also be appreciated that while ring forming operations may be successfully used in some cases on drop hammers the hammer die cost is initially high and the need for a multiplicity of preliminary shaping impressions may require the use of several hammers. Thus prior processes so far as I am aware are relatively expensive from the standpoint of utilizing costly equipment as well as resulting in wastage of material.

20 Referring to the drawings, the method will be disclosed in connection with a preferred form of ring spreader tool used in the preliminary shaping of a steel billet prior to the blocking and edging operations on a work piece.

As shown by Fig. 1, a supporting block or bed plate 1 is provided with a stationary die 2 mounted at one end of plate 1. Die 2 is formed with a semi-circular horn 3, horizontally disposed and having its curved edge 4 facing the curved edge 5 of a complementary horn 6 of a movable die 7. Die 7 is adapted for reciprocatory motion being slidably mounted in ways 8 of the bed 1, and as shown by Fig. 2, is offset upwardly of the die 2.

30 The dotted line representation of a steel bar or billet 9 is shown by Fig. 1 in position for movement of the horns together into an overlapping position as shown by Fig. 5. It will be noted in Figs. 1 and 2 that the billet is "split" having in its upper and lower surface longitudinal recessed portions as the V cuts 10. The bottom of the recesses or cuts are registered at the longitudinal center line of the billet. The length and width of the split between the ends of the billet is controlled by the size of the ring desired and the material being worked. As will be appreciated, the two sides of the split define the approximate internal circumference of the ring to be formed. The split may be conveniently made by suitable dies as in a drop forge hammer.

It will be seen from the drawings of Figs. 2, 4 and 5 that the billet is placed angularly against the tip of the stationary horn with one side of a recess centrally at the top edge of the horn. In this position the upper angular side of the adjacent V rests on the upper marginal edge surface of horn 3. The edges of the horns will thus apply pressure angularly against opposite sides of the bar and on opposite sides of the "split."

The method is especially adapted to work forging stock having a comparatively narrow range of forging temperatures, but may be used wherever economy of operations is desired. As a representative example of the new method of producing rings the steps in forming a ring from a block of steel such as AMS. 5642 Stainless will be discussed and the detail of the apparatus shown by the figures described. This steel is of the following analysis: C. .30, M. .85, Phos. .010, Sul. .009, Sil. .30, Ni. .63, Cr. .45, Mo. .22, GS. 6-8.

The bar or block of steel is first heated to approximately 2100 degrees. A tong handle as at 11 is formed and the block is split at 10 as in the dies of a drop hammer. A line through the center of the stock is thus provided. The split block is then reheated and placed on the stationary horn as in Figs. 1 and 2. Power is applied to move the slidable horn 6 for applying pressure against the opposite surface of the V cut and the two halves of the block are pressed to separate and open up into a ring shape. In steels of less toughness a single pass of the movable horn may form the desired circular shape. However, in the example of the above analysis steel two passes are necessary. The first pass spreads the sides of the block approximately half way and the piece is then reheated to temperature. A second pass is made with the reheated partially formed ring then spread to the extent shown by Fig. 4.

In the form shown by Fig. 4, the ring is reheated and placed in the dies of a drop hammer for ordinary blocking and finishing operations into the desired annular ring form.

It will be realized by those skilled in this art that a true circle is not necessary for a proper shaping of the ring to be worked for the blocking and finishing operation of the drop hammer die. The tolerances of the die are such that the metal at each end of the bar, when spread as in Fig. 4, may readily be hammered into the desired ring shape.

The ring as blocked out by the hammer is then placed in a usual press trimming punch and any flash is cut away to leave the ring in condition for finish machining.

The progressive formation of a ring from the split block of steel is shown by Figs. 6-10.

The apparatus shown by the drawings will now be specifically described. In Fig. 2 the bed plate 1 is shown mounted on a supporting member as a table 13 and is fixed thereon by a plurality of bolts 14. The stationary die 2 is in elevated position in overlying relationship to plate 1, being fixed on a spacer block 15 as by bolts 16. Block 15 is in turn fixed to plate 1 by bolts 17. Block 15 is also secured against movement by the mortise and tenon arrangement as at 18.

The horn 3 faces the other end of the plate 1 and is spaced from its surface to permit sufficient clearance for various dimensions in the thickness of the ring as will be obvious.

Movable die 7 is slidably mounted at the other

end of the plate 1 with its horn 6 facing horn 3. A spacer deck 20 is fixed by bolts 21 to the plate 1 (see Fig. 3). Ways 8 are formed by the sides 22 bolted at 23 to deck 20. Sides 22 at the top are inwardly flanged at 24. Roller plates 25 are fixed to flanges 24 to retain in a plurality of longitudinal spaced roller pockets 26 (see Fig. 1) upper rolls 27 for the die 7. The pockets 26 are formed in the underside of flanges 24. Lower rolls 28 are recessed in pockets 29 cut in the surface of a roller insert 30. Inserts 30 are embedded in slots cut longitudinally at each side adjacent the inner edges of sides 22. Upper and lower rolls are thus provided to embrace the marginal edges of the die 7 for its sliding movement relative to deck 20 when the die 7 is moved toward the stationary die 2.

At the rearmost end of die 7 and centrally thereof between ways 8 an abutment or pusher block 31 is secured as by bolts to the upper surface of the die. Block 31 is raised above the sides 22 and has a threaded engagement at 32 with the fore end of a piston rod 33 of a pneumatic or hydraulic pressure cylinder 34 mounted in any suitable manner so as to apply a direct thrust to the movable die 7.

As will be noted from Fig. 4, the piston 33 when fully extended causes the horn 6 to overlap horn 3 with the diametrical base line of horn 6 as at 35 directly superimposed over the diametrical base line of horn 3. The lower edge of horn 6 and the upper edge of horn 3 thus closely approximate a true circle around which the ring halves are spread by the die pressure in oppositely

35 directly parallel paths.

On the top of the sides 22 and extending cross-wise between them is a stop bar 36 bolted at each end to the sides as shown. Bar 36 lies in the path of block 31 and is located to terminate the 40 outward travel of the piston rod 33 when the horns are overlapped to the extent desired for formation of the ring on the apparatus.

It will readily be appreciated that semi-circular horns 3 and 6 may be provided with various dimensions so that rings of a smaller diameter 45 may be produced. In this event the rear edge of stop 36 may be moved rearwardly as may be needed by placing a check or other block against its edge and further limiting the outward thrust of the piston. In the embodiment of the apparatus illustrated by the drawings, the dies shown 50 are designed to produce a ring diameter of 12 inches.

What is claimed is:

Apparatus for spreading a bar of hard and 55 tough steel stock split between the ends thereof into circular form comprising a table support, a stationary die horizontally disposed at one end thereof having an arcuate semi-circular portion facing the opposite end of the support and overlying the table in parallel relation therewith, guideway structure mounted at the other end of said support and defining a horizontal path in adjacent parallel relation to said stationary die, a movable die in said guideway with rollers 60 pocketed at each side of the guideway embracing the top and bottom side edges of said movable die for rolling movement thereof, said movable die having a complementary arcuate semi-circular edge formed at its inner end and at its outer end portion having an abutment projecting upwardly of the sides of said guideway structure, a piston rod fixed to said abutment and fluid pressure means for extending said piston 65 to move said die toward and away from said stationary die, said guideway structure including 70

75

a transverse stop member fixed to the sides thereof and extending between the same above said movable die in the path of said abutment, said movable die being limited in its movement inwardly of said stationary die by the engagement of said abutment against said transverse stop and in said position overlying the stationary die with the arcuate portions of the dies forming a circle around which the split halves of a steel bar may be spread.

THOMAS R. LANDERS.
